GASOLINE DOOR GUARD

Budd Barr, Detroit, Mich.

Application September 6, 1950, Serial No. 12,075

Term of patent 7 years

(Cl. D14—6)

To all whom it may concern:

Be it known that Budd Barr, a citizen of the United States of America, and a resident of Detroit, in the county of Wayne and State of Michigan, has invented a certain new, original, and ornamental Design for a Gasoline Door Guard, of which the following is a specification, reference being had to the accompanying drawing, forming a part thereof, and wherein:

Fig. 1 is a side elevational view of a gasoline door guard, showing my new design;

Fig. 2 is a top plan view of the gasoline door guard shown in Fig. 1;

Fig. 3 is an end elevational view of the left-hand end of the gasoline door guard shown in Fig. 1;

Fig. 4 is a sectional view taken along lines 4—4 of Fig. 1; and

Fig. 5 is an end elevational view of right-hand end of the gasoline door guard shown in Fig. 1.

I claim:

The ornamental design for a gasoline door guard, substantially as shown.

BUDD BARR.
